9 Claims. (Cl. 117—17.5)

The developers normally used in electrophotography consist of a mixture of finely divided resinous toner and a carrier for the toner of somewhat larger particle size than the toner. The carrier is often of magnetizable material, e.g. iron filings, in order to enable the developer to be applied with the aid of a rotating magnetic roller to the surface of a latent electrostatic image.

The magnetic roller, which may be a permanent magnet or may be magnetized by an electric current, dips into developer powder contained in a trough beneath the roller. The iron filings, carrying the toner on their surfaces, adhere in brush-like formation to the magnetic poles of the roller and are applied in this form by the rotation of the roller to the surface of a charged electrophotographic material which has been exposed imagewise and is traversed over the roller. The toner is attracted electrostatically from the magnet to the photoconductive coating of the electrophotographic material and a visible image is formed. The developer, depleted in toner, is returned to the trough as the magnetic roller rotates.

This procedure has the disadvantage that the iron filings adhering to the roller become progressively depleted in toner and, as a result, the quality of the developed image progressively deteriorates.

It has accordingly been proposed to release the iron filings from an electromagnetically excited roller by periodically switching off the exciting current so that the roller can be charged anew with fresh toner from the trough in which the developer is agitated to keep it in constant movement. As such complete interruption of the exciting current produces an uneven developing effect, it has also been proposed to switch off the exciting current at the magnetic poles only which are on the circumference of the semicircle between the point of contact of the developer with the electrophotographic material and the point at which the roller dips into the developer in the trough. This proposal also fails to give the desired results because a certain residual magnetism persists at the magnetic poles after the exciting current has been switched off, so that the developer powder cannot drop off completely and therefore renewal of the developer takes place to a limited extent only.

Moreover, the iron filings always come to rest at the same place, namely near the point at which renewed magnetization of the poles occurs so that the mixing operation in the trough, which can be carried out at a limited speed only and which is intended to load the iron filings with new toner, cannot take place sufficiently rapidly. The roller therefore continually picks up the toner-depleted iron filings which have just been dropped as a result of the demagnetization.

The present invention provides an apparatus for developing latent electrostatic images comprising a trough to contain a developer mixture of iron filings and toner powder, an agitator in the trough, an electromagnetically excited iron roller for picking up developer from the trough and transferring it to the electrophotographic material to be developed, the iron roller being made of up of rotor plates having a number of windings to which exciting current is supplied intermittently, being cut off once in every revolution of the roller and a covering of synthetic plastic

2

material, and a deflector plate which coats with the portion of the roller traveling away from the electrophotographic material and towards the developer contained in the trough to deflect towards the wall of the trough developer shed by the roller while the current is cut off.

By means of this apparatus, the above-mentioned disadvantages are eliminated. The residual magnetism on the magnetic poles during the period in which the current is switched off can no longer hold the iron filings of the developer because of the plastic coating. The developer powder shed by the roller is deflected by the deflector plate to a place remote from the pick-up point of the electromagnetic roller, so that it can be fully recharged with toner powder by the agitator in the trough before it is again taken up by the electromagnetic roller. Rotor plates are understood as components such as are used in the electrical industry for the production of rotors in electric motors.

The laminations of the roller consists of relatively thin soft iron sheets placed side by side with layers of insulating material between them. The shape of these plates corresponds to the cross section of the intended roller. If the notches provided for the windings are even in number, particularly good results can be obtained. When the individual rotor blades are placed together along the rotational axis and the poles are wound, the magnetic roller to be used as provided by the invention is formed. Any desired length may be produced.

The covering on the roller may consist of any suitable insulating plastic which is solid at normal temperatures. Examples of suitable plastics are thermoplastics, such as polyolefins, e.g. polyethylene and polypropylene, polyvinyl compounds such as polyvinyl chloride, polyamides and polyesters. Good results are also obtained with thermosetting resins, e.g. phenolformaldehyde resins. Particularly favorable results are obtained with plastics such as those used for insulating purposes in transformers; they are described, for example, in the handbook of Messrs. Schramm, Lackund, Farbenfabrik AG, "Elektro-Isolierlacke."

The plastic coating can be applied by placing the magnetic roller in a mold, the gap between the inner walls of mold and the surface of the magnetic roller being greater than the thickness of the plastic coating which is to be produced on the surface of the roller. The intermediate spaces are now filled with a substance which contains unhardened components of a resin mixture together with a hardener. The whole is then allowed to stand for 20-30 hours, during which time the plastic hardens completely. After removing the roller from the mold, it is advantageous for the surface of the plastic coating to be evened and smoothed by turning.

The plastic covering may also be applied to the roller by painting on a mixture of the plastic substance and a hardener. In such cases, the thickness of the painted coating is advantageously considerably greater than the thickness finally required. After hardening out, the surface of the plastic coating is again finished by turning and polishing. Plastic coatings, particularly thermoplastic coatings, can also be applied to the roller surface in the form of ready made foils by wrapping and, where necessary, fusing.

The thickness of the plastic coating on the surface of the electromagnetic roller is generally between 0.2 and 1.0 mm. preferably 0.4-0.5 mm., but lesser or greater thicknesses can also be successfully used.

The surface of the plastic coating on the magnetic roller may be made electrically conducting and may be provided with a bias voltage with respect to the surface of the photoconductive layer of the electrophotographic material or it may be grounded. This is particularly advantageous in the case of the development of latent electro-

static images which, because of inadequate exposure, have a residual charge in the image-free parts.

The surface can, for example, be made conductive by treatment with a dispersion of silver particles in a suitable dispersion agent, e.g. the so-called "Leitsilber" (conducting silver), or it can be coated with metal. Good results are also obtained by the application of a thin metal foil to the roller.

The deflector plate extends over the whole width of the electromagnetic roller. The distance of the deflector plate from the surface of the roller should be kept as small as possible. The length of the surface of the deflector plate over which the toner-depleted carrier runs should be as great as possible. The deflector plate should discharge the carrier near to the wall of the trough. The deflector plate can be joined underneath with the normally used securing devices to the wall of the vessel.

The apparatus may include a container for toner powder adjacent the trough and means for periodically delivering measured quantities of toner powder from the container to the trough.

One embodiment of developing apparatus according to the invention will now be described in more detail, by way of example, with reference to the accompanying diagrammatic drawings, in which:

FIGURE 1 is a transverse section through the developing apparatus,

FIGURE 2 is a plan view,

FIGURE 3 is a longitudinal section through the developing apparatus,

FIGURE 4 shows the current supply member in cross-section, and

FIGURE 4a shows the current supply member in plan view.

As shown in FIGURES 1 and 2, the apparatus includes an electromagnetically excited roller 1 having a shaft 2 which is journaled in bearings 3 and 4 and is driven by the gears 5, 6 and 7. The windings 9 of the roller 1 receive current from a source, not shown, of direct current via individual slip rings 10.

As shown in FIGURES 3, 4 and 4a, the roller 1 has twelve grooves 9' containing six separate windings which are excited by means of six slip rings 10 which coact with the brushes 26. The roller 1 also has a coating 11 of synthetic plastic material. Between points 12 and 13, the slip rings 10 are provided with means for interrupting the current. The roller rotates anticlockwise as viewed in FIGURE 4 and, as soon as the windings 9 have passed the point 13, they are deprived of current. The developer carried by the roller is then dropped off and is deflected by a deflector plate 14 to the outer edge of the developer trough. The discarded developer works its way very slowly back from the outer edge of the developer trough 14' to the agitator 15 in the trough and is taken up by the agitator and, after intensive mixing, passed to the point 12, at which magnetization of the roller recommences, and is there taken up by the roller. The plastic coating 11 on the magnetic roller 1 ensures that after the current has been switched off at the point 13 the developer will not remain attracted by residual magnetism.

The trough is replenished with toner in a simple manner and without dust by the following mechanism:

A container 17 (FIG. 3) contains a certain quantity of toner for purposes of replenishment. As the toner is consumed, the trough is replenished with toner from the container 17 by dosing plungers 18. End plates 19 on the plungers 18 normally close the feed opening 20 in the wall of the container 17 and the plungers carry sealing sleeves 21. The plungers, which are fitted with return springs 24, are actuated by rocker arms 22 from a motor-driven eccentric 23, which is driven at a speed appropriate to requirements. The toner in the container 17 is agitated by a vane 25 which is vibrated by a rocker magnet.

It will be obvious to those skilled in the art that many modifications may be made within the scope of the present

invention without departing from the spirit thereof, and the invention includes all such modifications.

What is claimed is:

1. Apparatus for developing latent electrostatic images comprising a trough adapted to contain a developer having a magnetic component, a rotatable electrically magnetizable roller mounted in the trough, the roller having a plurality of separate windings and an insulating layer on the roller surface, means for supplying and interrupting an electric current to at least one of the windings during rotation of the roller to thereby successively magnetize and demagnetize portions of the roller surface, and deflecting means mounted adjacent the roller.

2. Apparatus according to claim 1 in which the insulating layer is a plastic material.

3. Apparatus according to claim 1 including a container adapted to contain toner mounted adjacent the trough and means for delivering measured quantities of toner to the trough.

4. Apparatus according to claim 1 in which the roller comprises a plurality of rotor plates.

5. Apparatus according to claim 1 in which the roller is iron.

6. Apparatus according to claim 1 in which the deflecting means is a plate.

7. Apparatus according to claim 1 in which the trough also contains means for agitating the developer.

8. A process for applying a developer to a latent electrostatic image which comprises electrically generating a magnetic field in portions of a surface of a rotatable applicator submerged in a body of developer having a magnetic component, rotating the said portions of the surface carrying developer thereon into contact with the latent electrostatic image, rotating the said portions of the surface out of contact with the electrostatic image and interrupting the electric current, thereby eliminating the magnetic field from said portions of said surface, and passing excess developer from said portions of said surface back into the body of developer at a point remote from the initial position of the developer in the body.

9. A process according to claim 8 in which toner is intermittently added to the body of developer.
